CLAIM

The ornamental design for a molded tortilla pocket, as shown and described.

DESCRIPTION

FIG. 1 is a top, front perspective view of a molded tortilla pocket;

FIG. 2 is a front elevational view of the molded tortilla pocket;

FIG. 3 is a rear elevational view of the molded tortilla pocket;

FIG. 4 is a left side view of the molded tortilla pocket;

FIG. 5 is a right side view of the molded tortilla pocket;

FIG. 6 is a top plan view of the molded tortilla pocket; and,

FIG. 7 is a bottom plan view of the molded tortilla pocket.

The broken lines shown in FIGS. 2–5 illustrate portions of the molded tortilla pocket that form no part of the claimed design. The broken lines illustrating the hand and the food inside of the molded tortilla pocket are environment, while the remaining broken lines in FIG. 1 illustrate portions of the molded tortilla pocket that form no part of the claimed design. The dash-dot-dash broken lines in FIGS. 1–7 illustrate the boundary of the claimed design which forms no part thereof.

1 Claim, 6 Drawing Sheets
